UNITED STATES PATENT OFFICE.

WARREN L. EDMONDSON, OF WASHINGTON, DISTRICT OF COLUMBIA.

RENEWABLE CUTTING-TOOTH POINT.

1,340,385.

Specification of Letters Patent. Patented May 18, 1920.

Application filed July 29, 1919. Serial No. 313,978.

To all whom it may concern:

Be it known that I, WARREN L. EDMONDSON, a citizen of the United States, residing at Washington, in the District of Columbia, 5 have invented certain new and useful Improvements in Renewable Cutting-Tooth Points, of which the following is a specification.

This invention relates to new and useful 10 improvements in renewable cutting tooth points, and pertains more particularly to cutting points for use with ditching and grading machines and the like.

The primary object of the invention is to 15 provide a tooth which has a novel form of detachable cutting point so that the latter may be easily and quickly removed when worn or otherwise incapacitated, and a new point inserted in its place.

20 The invention further aims to provide a point which involves a minimum of material, so that upon discarding thereof the resultant waste is reduced to the least possible, and at the same time to thus economize in 25 the initial course of production.

The invention further aims to provide a connection between the point and the shank 30 of the tooth which will effectively support the point and allow its disconnection and 35 the connection of a new point, and which will also support the point so that the stresses imposed there upon will be assumed by the parts without likelihood of breakage.

Further and other objects will be later set 40 forth and manifested in the course of the following specification.

In the drawings:

Figure 1, is a vertical sectional view taken 45 through a bucket and showing the present invention applied to the bottom and a side of the cutting bar thereof.

Fig. 2, is an enlarged view of the bottom tooth in longitudinal section.

Fig. 3, is a bottom plan view of Fig. 2.

45 Fig. 4, is a top plan view of the shank with the point removed.

Fig. 5, is a front end elevation of Fig. 4.

Fig. 6, is a side elevation of the cutting point.

50 Fig. 7, is a rear end elevation of Fig. 6.

Fig. 8, is an enlarged section on the line 8—8 of Fig. 1.

Fig. 9, is a top plan view of the side tooth of Fig. 8 and,

Fig. 10, is a section in a line 10—10 of 55 Fig. 9.

The invention is shown applied to a bucket B, having the usual substantially U-shaped cutting blade C, at its front edge, and involves a shank 1, which is secured to the 60 cutter bar by means of bolts and nuts 2. The forward portion of the shank is provided with a socket-like part 3, of somewhat V-form so as to wedgily receive the cutting edge of the cutter bar C, as depicted 65 in the drawings. The shank at its extreme front end is formed to have an upper inclined face 4, and rearwardly and downwardly inclined parts 5, the parts 4 and 5, conjointly forming a somewhat V-shape 70 configuration. The inclined end face 4, is formed with a dovetail groove 6, centrally between its sides, and with a preferably slightly inclined shoulder 7, at the lower end of the groove, which shoulder is formed so 75 as to provide a flat abutting wall for a purpose later set forth. This shoulder 7, is at substantially right angles to the longitudinal axis of the shank so as to have maximum resistive property as will be now described. 80

The removable cutting point includes a body having an inclined upper face 8 and a flat bottom 9, the two conjointly forming a somewhat V-shaped configuration, with the rear end of the face 8, extending beyond the 85 inner end of the bottom 9. A dovetail projection or tenon 10, is formed on the rear of the inclined part 8, and at its lower end is extended and enlarged and provided with a depending foot 11, the latter shaped and 90 formed so as to abut the shoulder 7, while the inclined parts 5 of the shank 1 are engaged with downwardly and rearwardly inclined parts 12—12, shaped to form a close or tight fitting joint with said inclined parts 5. 95 The parts 12, 12, are disposed on opposite sides of the foot 11, and are of greater length than the latter and of greater inclination than the foot extending beyond the rear of the latter. The tenon acts to reinforce the 100 cutting point, while the foot 11, functions to also reinforce the bottom part 9 of the point. The foot 11 is thus backed by a considerably thickened mass of metal and by

abutting the shoulder 7 the latter will, due to its vertical disposition, assume all longitudinal thrusts or stresses to which the point is inherently subjected in the performance of its functions.

In the form of the invention shown at the top of Fig. 1 and Figs. 8, 9 and 10, wherein one only of the teeth used at the side of the cutter part is illustrated, the point is formed 10 with a wall 12 of greater acute angularity than the wall 12 in the instance of the tooth applied to the bottom of the cutter bar, so that the point will extend outwardly of the outer face 14 of shank 1 as depicted in Fig. 8 15 of the drawings, the face 14 of shank 1 being curved so as to merge into the outer face 9 of the point.

In both forms of the invention, the point and the shank are formed with registering 20 openings through which a rivet 15 is passed, the rivet being inclined and having its ends headed and countersunk into the point and shank as shown. This rivet functions to prevent disengagement of the point from 25 the shank by sliding of the point, and is not subjected to any of the stresses or strains imposed upon the point during working of the latter. In this regard it will be further noted the opening in the point for the 30 reception of the rivet 15 extends through the dove-tail projection 10, so that the point is not appreciably weakened.

It will be apparent from the foregoing that all thrusts imposed upon the point endwise thereof will be taken up not only by the central shoulder 7 but also by the inclined parts 5 which are disposed one on each side of the shoulder and have an angularity differing from that of the shoulder, 40 the latter and the parts 5—5 being engaged by the foot 11 and the parts 12—12 respectively. In addition lateral thrusts or strains imposed upon the point will be taken up in part by the dove-tail tenon 10.

It will further be seen from the foregoing that the tooth as well as the shank are devoid of any frail or weak portions which are likely to become broken or fractured or otherwise rendered unserviceable in use. 45 By referring to Fig. 1 it will be seen that the joint formed between the parts *i. e.* point and shank, extend into the point so that the latter is provided with an upper part of equal thickness, and with corresponding 50 strength. Further the wall 12 is short so as to require a minimum of material in the manufacture of the point, and consequently the point can be used down to the part marked X in Fig. 1, so that upon discard of 55 the point the least possible material is wasted.

What is claimed is:—

1. In a tooth for ditching machines and the like, a shank having a downwardly and 60 outwardly inclined upper face formed with

a dovetail groove centrally between its sides and formed with downwardly and rearwardly inclined parts on opposite sides of the groove with a shoulder at and extending across the lower end of the groove, said shoulder being substantially at right angles to the longitudinal axis of the shank, a removable cutting point having a bottom wall, an inclined front face, and a dovetail projection on the rear of the front face receivable in said groove, the lower end of the dovetail projection being extended and formed with a depending foot which conformably engages the shoulder, said point having a part on each side of the foot and 70 of greater length and inclination than the latter and engageable with the downwardly and rearwardly inclined parts of the shank and a rivet passed through the point and shank and extending through the top and 75 bottom faces of the dovetail projection. 80

2. In a tooth for ditching machines and the like a shank having a substantially V-shaped end formed with a groove, said groove forming a transversely central shoulder at the lower end thereof which shoulder is substantially at right angles to the longitudinal axis of the shank, and a cutting point of substantially V-form having a 90 tenon received in the groove and having a central foot extended out from the lower end of the tenon and engaged with said shoulder and having parts on opposite sides of the tenon and foot of different inclination than that of the foot to engage the respective V-faces of the shank. 95

3. In a tooth for ditching machines and the like, a shank having a substantially V-shaped end formed with a groove which latter extends through the upper face and 105 the apex of the V-end so as to form an abrupt shoulder at the apex and a cutting point having a tenon on its rear received in said groove, said tenon being extended downwardly and enlarged at its lower end 110 and formed with a foot to abut the shoulder and having a pair of parts on opposite sides of the foot to engage the lower face of the V-end of the shank, said parts being of greater length than the foot and extending 115 toward the cutting point of the teeth and rearwardly beyond the rear end of the foot.

4. In a tooth for ditching machines and the like, a shank having a groove and an abrupt shoulder at the base of the groove 120 and depending therefrom, and a cutting point of the same width as that of the shank seated on the latter and having a tenon on its under face receivable in the groove and having a foot extending outwardly from 125 the tenon and beyond the outer face thereof to engage the shoulder.

5. In a tooth for ditching machines and the like, a shank having a groove arranged at an incline to the shank and a shoulder at 130

the base of the groove, a cutting point having downwardly and rearwardly extending side parts underlapping the bottom of the groove, and abutting the end parts of the shank on opposite sides of the groove, a tenon on the rear face of the point extending upwardly from said parts, and an enlarge-

ment on the tenon at the bottom end thereof between said parts, said enlargement being shaped to conformably engage said shoulder 10 and having a different inclination from that of the said end parts of the cutting point.

In testimony whereof I affix my signature.
WARREN L. EDMONDSON.
